UNITED STATES PATENT OFFICE.

FRANK R. WENTWORTH, OF RUSSELL, KANSAS.

DESIGN FOR A WATCH CHARM, PENDANT, OR SIMILAR ARTICLE.

Application filed October 18, 1921. Serial No. 508,624. Term of patent 3½ years.

To all whom it may concern:

Be it known that I, FRANK R. WENTWORTH, a citizen of the United States, residing at Russell, in the county of Russell and State of Kansas, have invented a new, original, and ornamental Design for Watch Charms, Pendants, or Similar Articles, of which the following is a specification, reference being had to the accompanying drawing, forming part thereof, and wherein—

Figure 1 is a perspective view of a watch charm, pendant, or similar article showing my new design,

Figure 2 is a side view thereof,
Figure 3 is a front elevation thereof,
Figure 4 is a top plan view thereof, and
Figure 5 is a bottom plan view.

I claim:

The ornamental design for a watch charm, pendant, or similar article as shown.

FRANK R. WENTWORTH.
